UNITED STATES PATENT OFFICE.

WILLIAM GEORGE CANNON, OF SOUTHWARK, COUNTY OF SURREY,
ENGLAND.

RADIATOR.

SPECIFICATION forming part of Letters Patent No. 423,728, dated March 18, 1890.

Application filed December 16, 1889. Serial No. 333,899. (No model.) Patented in England May 8, 1889, No. 7,684.

To all whom it may concern:

Be it known that I, WILLIAM GEORGE CANNON, gas and hot-water engineer, and manufacturer of hot-water apparatus, a subject of the Queen of Great Britain, residing at 106 and 107 London Road, Southwark, in the county of Surrey, England, have invented certain new and useful Improvements in Radiators, and in the utilization of the same for warming and ventilating, (for which I have obtained a patent in Great Britain, No. 7,684, bearing date May 8, 1889,) of which the following is a specification.

My invention relates to the construction of that class of metallic radiating-coils for heating purposes in which groups of vertical radiating-pipes are used, such pipes containing steam or hot water and communicating heat to the surrounding atmosphere; and the objects 20 of my invention are to effect improvements in the method of forming the junctions, in affording increased facilities for erecting, attaching, and detaching the pipes, making good the joints, and otherwise manipulating the same. 25 In carrying out my invention I form the vertical pipes with side passages at or near each end, for the circulation of the water or steam through the same. Suitable sockets may be cast upon the faces of the lower main casting 30 and upper horizontal pipes, and corresponding flanges or rings or other suitable provisions upon the vertical pipes, round which the elastic washers are placed to secure fluid-tight joints; or I may form such joints of flat 35 surfaces with planed faces, metal and metal, or by equivalent means. The pipes are united to the main casting by means of bolts, screws, studs, and nuts, clips, lugs, or equivalent means, the joints being made good by rubber, 40 asbestos, woodite, or other suitable rings, washers, or packing red-lead gasket, or otherwise, as aforesaid. The main casting may be fitted with single, double, treble, or other sets or groups of vertical pipes, either on one side 45 or on both sides, special provision being made in the main casting and in or upon the detachable pipes to receive the bolts, screws, studs, or nuts and washers, clips, lugs, or equivalent devices, as required.

50 By means of the aforesaid arrangements I

am enabled to remove and refix any one or more of the vertical pipes without disturbing and of the others or the main casting itself. The main casting is preferably fitted with 55 chambers to admit the external air, by means of suitable junctions, such air rising through suitable openings to the vertical pipes, and being thereby warmed before it mixes with that in the apartment.

My invention may be used with either steam 60 or water, and when water is used plugs, siphons, or automatic vents or taps are fitted to the main casting, or permit the escape of air when filling the apparatus with water; and in order that my said invention may be particularly described and ascertained reference is hereby made to the accompanying drawings, in which similar letters of reference indicate corresponding parts.

Figure 1 is a front elevation of a radiator. 70 Fig. 2 is a sectional elevation showing the method of fitting a row of pipes on one side only of the main casting. Fig. 3 is a sectional elevation showing the method of fitting sets of vertical pipes on both sides of the main 75 casting; and Fig. 4 is a horizontal section on the line $\alpha\alpha$ of Fig. 3.

Referring to Figs. 1 and 2, a is the main casting, and a' is a longitudinal channel formed in a vertically-projecting extension, which 80 constitutes a part of the main casting, and operating as a horizontal pipe in connection with the vertical pipes $d d$. The vertical face of the wall of the horizontal pipe a' is shown formed with openings and sockets to receive 85 the laterally-projecting collars cast on the lower ends of the pipes $d d$. These junctions are secured by screws $e e$, as shown in Fig. 2. Packing-rings may be used to render the junctions water and steam tight.

b is the casting to which the upper ends of the pipes $d d$ are secured, by means of screws $f f$, Fig. 1, passing through ears formed upon the pipes $d d$ for that purpose. This casting forms a longitudinal channel, in communication 95 with the upper ends of the pipes, the joints being also shown constructed for packing-rings.

$c c$ are the circulating-pipes, in communication with any suitable boiler or other heat- 100

ing apparatus. *g* is an ornamental cover laid upon the apparatus, under which plugs, siphons, or automatic vents or taps may be fitted to let off steam or air, or to ascertain when the radiator is filled with water.

I sometimes fit the radiator so as to admit fresh air from the outside of the house by a pipe *h*, passing through the wall *k*. The air is thus led into an inclosed chamber *m*, extending the whole length of the radiator and closed at the ends. From the chamber *m* the air passes into the chamber *n*, also closed at the ends, and located along the inner sides of the vertical pipes *d*. The incoming air passes from the chamber *n* between the pipes *d d*, as indicated by the arrows, whereby fresh warm air may be admitted to the apartment.

Referring to Figs. 3 and 4, (of which Fig. 1 is a front elevation,) the channels *a²* and *b* are formed to receive sets of pipes *d d* on both sides, each set of pipes being secured in a similar manner to that shown in Fig. 2. This form and arrangement of my invention may also be fitted with air-chambers *m n*, as shown in Fig. 2.

Although I have shown the pipes cast in sets of three communicating at each end, I do not confine myself to that or any number, as it is obvious that the number may be varied and other sectional forms may be used.

I claim—

1. The combination, in a radiator, of a hollow base having an upwardly-projecting extension forming a longitudinal channel, with a series of vertical pipes independently connected to the vertical face of the upwardly-projecting extension, substantially as described.

2. The combination, in a radiator, of a base composed of a hollow casting having an up-

wardly-projecting extension forming a longitudinal channel and provided in its vertical face with lateral sockets, with the independent vertical pipes, each having at its lower end a lateral collar detachably secured to a lateral socket in the base, substantially as described.

3. The combination, in a radiator, of a base composed of a hollow casting having an upwardly-projecting extension forming a longitudinal channel and provided in its vertical face with lateral sockets, with the independent vertical pipes, each having at its lower end a lateral collar detachably secured to a socket, and a hollow casting extending along the inner sides of the pipes at their upper end portions and detachably connected to and communicating with the said pipes, substantially as described.

4. The combination, in a radiator, of the hollow closed base formed integral with an upwardly-projecting extension constituting a longitudinal channel and having a vertical face provided with horizontal sockets, a series of independent vertical pipes, each having on the inner side of its lower end a horizontal collar connected to one of the sockets, a screw passing horizontally through the collar of each pipe and engaging the upward extension of the base, and a hollow casting located along the sides of the pipes at their upper ends and communicating therewith by horizontal passages, substantially as described.

Dated this 25th day of November, 1889.

WILLIAM GEORGE CANNON.
